(Cl. D72—1)

To all whom it may concern:

Be it known that I, John S. McRea, a citizen of the United States of America, and a resident of New York city, county and State of New York, have invented a new, original, and ornamental Design for a Combined Siren and Spotlight or the like, of which the following is a specification, reference being had to the accompanying drawing, forming part thereof, in which:

Fig. 1 is a side elevational view of a combined siren and spotlight showing my new design;

Fig. 2 is a front elevational view thereof;
Fig. 3 is a rear elevational view; and
Fig. 4 is a top plan view.

I claim:

The ornamental design for a combined siren and spotlight or the like, as shown.

JOHN S. MCREA.
